CLAIM

I claim the ornamental design for a ligature for wind instruments, as shown and described.

DESCRIPTION

FIG. 1 is a first exploded view of a ligature for wind instruments showing my new design;
FIG. 2 is a second exploded view thereof;
FIG. 3 is a first perspective view thereof;
FIG. 4 is a second perspective view thereof;
FIG. 5 is a top view thereof;
FIG. 6 is a bottom view thereof;
FIG. 7 is a front view thereof; and,
FIG. 8 is a right side view thereof.
